TIMING DEVICE

Thomas H. Sheehan, Detroit, Mich.

Application February 15, 1947, Serial No. 728,753

9 Claims. (Cl. 161—1)

1

This invention relates to a timing device and more particularly to a mechanical device of this type adapted for timed actuation of control mechanisms.

Among the objects of this invention is the provision of a mechanical timing device for producing a snap movement after the elapse of a desired time interval and which effects instantaneous response of a control mechanism.

Another object of my invention is to provide a mechanical timing device which can be accurately adjusted for different time intervals and which is adapted for use with a great variety of both mechanical as well as electrical control systems.

In the drawings:

Fig. 1 is a side view partly in section of a door stop mechanism embodying one application of my invention.

Fig. 2 is an end view of the structure shown in Fig. 1.

Fig. 3 is a top view of the locking means provided at the upper end of the door stop.

Fig. 4 is an end view of the fluid reservoir showing the manner in which it is mounted on its support bracket.

Fig. 5 is a view taken along the line 5—5 of Fig. 1.

Fig. 6 is a view taken along line 6—6 of Fig. 4.

Referring to the drawings, and particularly to Fig. 1, I have shown my timing device employed as an automatic door closer in which a bolt 10 is mounted for vertical movement on a door plate 11 which may be secured adjacent the lower edge of a door. The bolt is provided with a stopper 12 at the lower end arranged to engage a stationary pin 41 in a floor surface to hold the door in a fixed position and is urged upwardly by a compression spring 13 acting between flange 19 at the bottom of plate 11 and washer 42 which is retained on the bolt. A spring detent 14 mounted on plate 11 is arranged to engage with a shouldered portion 15 on bolt 10 and thereby lock the bolt in its lowered position against the tension of spring 13.

To effect tripping of the spring detent after a timed interval, there is provided a fluid filled cylinder 16 rotatably mounted at one end thereof on plate 11 by means of pin 17. The pin and cylinder are supported between the legs of U-shaped bracket 18 which is fixedly secured to the door plate 11 with its open end extending downwardly and away from bolt 10. There is also pivotally mounted on pin 17 a yoke 21 which extends over the cylinder and rotates independently thereof. A small detent 22 projecting outwardly from arm

2

23 of yoke 21 and into a larger opening 24 in bracket 18 limits the pivotal movement of the yoke as is best shown in Fig. 6. The rear end of cylinder 16 is provided with a stop plate 25

5 which is adapted to abut against and rotate yoke 21 as the cylinder pivots downwardly. When the cylinder pivots upwardly its upper surface contacts the yoke and pivots it in the other direction. At the lower end of arm 23 directly below pin 17 there is secured one end of a tension spring 20 the other end of which is secured to an arm 26 which extends outwardly from the upper end of bracket 18. A screw and nut arrangement 27 permits adjustment of the tension in the spring.

10 When the cylinder is in the raised position, as indicated by broken line 28, it will be observed that the axis of the spring 20 is to the left of pivot pin 17 and the yoke 21 is retained in its uppermost position. When the cylinder is in the 15 position indicated by lines 29, spring 20 lies to the right of pin 17 and stop 25 has moved yoke 21 to the other side of center position where it is snapped rapidly downwardly by spring 20.

The movement of the cylinder is coordinated 20 with the release of spring detent 14 by an engaging lug 30 which is secured to the detent and adapted to receive a sharp blow from a pin 35 projecting laterally from the rear end of the cylinder. Lug 30 is arranged to be struck by pin 35 and retract detent 14 from shoulder 15 as cylinder 16 is moving downwardly at its greatest velocity.

Within the cylinder there is provided a ball member 40 arranged to travel through the liquid 25 from one end of the cylinder to the other. The ball member must be heavy enough to produce sufficient leverage as it approaches the outer end of the cylinder to overcome the tension of spring 20 as well as the resilience of detent 14 and its 30 frictional engagement with shoulder 15 on bolt 10.

At a suitable position on bolt 10 there is provided a stop member 31 which extends through the bolt perpendicular to plate 11. As the bolt moves upwardly, under the force of spring 13, 35 the outer end of stop 31 abuts against the underside of cylinder 16 and carries it upwardly to its starting position 25. The inner end of stop 31 extends into a guide 32 formed in plate 11 and prevents the bolt from turning. A pivotal catch 40 33 at the upper end of plate 11 is arranged to be moved into engagement with the top of bolt 10 when it is desired to maintain the stopper 12 in the pin engaging position although detent 14 45 may have been released by the action of the cylinder.

55

In the uncocked condition cylinder 16 is held in the position indicated by lines 28 by stop member 31 which is raised by spring 13. At this time ball 40 rolls downwardly in cylinder 16 toward pivot 17 and spring 20 lies to the left of center position. When stopper 12 is depressed, detent 14 engages shoulder 15 and retains bolt 10 in the lowered position. At the same time cylinder 16, by reason of its own weight and the weight of the liquid within it, rotates downwardly about pivot 17 until stop plate 25 abuts against yoke 21, that is, the position indicated by full lines in Fig. 1. At this time ball 40 is adjacent the pivoted end of the cylinder and its effective weight or leverage is insufficient to overcome the tension of spring 20 on yoke 21. However, since the free end of the cylinder is disposed at a lower level than the pivot end, ball 27 begins to travel slowly through the liquid toward the lower end. As the ball travels toward the outer end of the cylinder and away from pivot 17, its leverage increases and after the elapse of a desired time interval the ball reaches a point where its effective weight or leverage plus the weight of the cylinder and the liquid overbalances spring 20 and causes yoke 21 to be snapped over center in a downward direction. This movement of the yoke releases the cylinder and permits it to fall very rapidly to the position indicated by line 29 in Fig. 1. In falling the cylinder accumulates considerable momentum and causes pin 35 to strike lug 30 a heavy blow to disengage detent 14 from shoulder 15 and effect an instantaneous release of bolt 10. The bolt then moves upwardly under the influence of spring 13 and stop member 31 carries the cylinder back to its raised position 28. In so doing the cylinder strikes yoke 21 and snaps it back over center to the starting position and the mechanism is ready for another cycle of operation.

It will thus be observed that the timing device of my invention is of simple construction and yet operates very effectively. Latitude in the duration of the time interval may be obtained in several ways, that is, adjustment of the tension in spring 20, the amount and viscosity of the liquid in the cylinder and the diametral difference or clearance between the ball and the inside diameter of the tube. I have found that lubricating oil serves satisfactorily as a liquid within cylinder 16 where large ambient temperature changes are not encountered. In applications which have a large ambient temperature range, kerosene has been found more satisfactory and it is also possible to make arm 26 a bimetal thermal element in order to change tension on spring 20 and thereby compensate for liquid viscosity changes in cylinder 16 in relation to ambient temperature changes. The improved snap action resulting from employing an over-center spring as described adapts the device for use in many different applications, especially in conjunction with electrical switches and circuit breakers where instantaneous release is necessary if arcing between the contacts is to be avoided.

I claim:

1. A timing device comprising a support, a reservoir containing a body of liquid and pivotally supported on said support, over-center resilient means acting between said reservoir and said support, said resilient means adapted to oppose downward pivotal movement of said reservoir in one over-center position and accelerate said movement in the other over-center position, and gravity influenced means located in said body of

liquid within said reservoir and arranged to travel away from the axis of pivoting of said reservoir and thereby overcome the tendency for said resilient means to oppose downward pivotal movement of said reservoir whereby said over-center resilient means passes over to the other side of center position and abruptly accelerates said downward pivoting movement of said reservoir.

5 10 15 20 25 30 35 40 45 50 55 60 65 70 75

2. A timing device comprising a support, a reservoir containing a body of liquid and pivotally supported on said support, over-center resilient means acting between said reservoir and said support, said resilient means adapted to oppose downward pivotal movement of said reservoir in one over-center position and accelerate said movement in the other over-center position, means for adjusting the force exerted by said resilient means on said reservoir to increase or diminish its influence on the downward pivoting movement of the reservoir, and gravity influenced means located in said body of liquid within said reservoir and arranged to travel away from the axis of pivoting of said reservoir and thereby overcome the tendency for said resilient means to oppose downward pivoting movement of said reservoir whereby said over-center resilient means passes over to the other side of center position and abruptly accelerates said downward pivoting movement of said reservoir.

3. A timing device comprising a support, a reservoir containing a body of fluid and pivotally supported on said support, releasable stop means arranged to limit the downward movement of said reservoir, over-center resilient means operatively connected to said stop means and to said support, said resilient means adapted to oppose downward pivotal movement of said reservoir in one over-center position and accelerate said movement in the other over-center position, and gravity influenced means within said cylinder adapted to travel away from the axis of pivoting of said reservoir and thereby overbalance said stop means whereby said resilient means passes to the other side of center position and assists said gravity influenced means in abruptly accelerating the downward pivotal movement of said cylinder.

4. A timing device comprising a support, a reservoir containing a body of fluid and pivotally supported on said support, pivotal stop means arranged to retain said reservoir in a position inclined downwardly from the axis of pivoting, over-center resilient means operatively connected to said stop means and to said support, said resilient means adapted to oppose downward pivotal movement of said reservoir in one over-center position and accelerate said movement in the other over-center position, and gravity influenced means with said reservoir adapted to travel away from the axis of pivoting of said reservoir and overbalance the restraining force exerted by said over-center resilient means on said stop means whereby said over-center resilient means shifts to the other side of center position and produces a downward snap movement of said reservoir.

5. A device for producing timed actuation of a control mechanism comprising a pivotally supported reservoir containing fluid, pivotal stop means adapted to limit the downward pivotal movement of said reservoir, over-center resilient means connected to said stop means and arranged to oppose downward pivotal movement of the cylinder in one over-center position and accelerate said movement in the other over-center position, control means arranged to be actuated

by the pivotal movement of said reservoir, and gravity influenced means within said reservoir adapted to travel away from the axis of pivoting of said reservoir and thereby overbalance said stop means whereby said resilient means passes to the other side of center position and produces a downward snap movement of the reservoir which is transferred to said control means as an abrupt actuation thereof.

6. A device for producing timed actuation of a control mechanism comprising a cylindrical reservoir containing liquid and pivotally supported adjacent one end thereof, a rolling member within said reservoir arranged to travel from the supported toward the free end thereof under the influence of gravity, mechanism control means arranged to be actuated by the pivotal movement of said reservoir, a releasable stop member arranged to limit the pivotal movement of said reservoir, and over-center resilient means operatively connected with said stop member, said over-center means arranged to oppose the gravitational influence of said rolling member until the effective leverage of said rolling member and the weight of said reservoir and liquid overbalance the restraining influence of said stop means whereby said downward pivotal movement is abruptly accelerated and said mechanism control means is abruptly actuated.

7. A timing device comprising a support, a reservoir containing a body of liquid and pivotally supported on said support, gravity influenced means within said reservoir arranged to travel through said liquid toward and away from the axis of pivoting of said reservoir, over-center resilient means operatively connected between said reservoir and said support which opposes downward pivotal movement of the reservoir in one over-center position and accelerates said movement in the other over-center position, means for holding said reservoir in an uncocked position inclined upwardly to said axis of pivoting to permit said gravity influenced means to travel toward said axis of pivoting, and releasable latch means for permitting said reservoir to pivot downwardly when cocked to a position inclined downwardly from said pivotal axis whereby said gravity influence means travels to a point away from said pivotal axis where its effective leverage together with the weight of said body of liquid and said reservoir overbalance said resilient means and cause said resilient means to pass over to the other side of center position and

thereby snap said reservoir downwardly to a position below said cocked position.

8. A timing device comprising a support, a reservoir containing a body of liquid and pivotally supported on said support, gravity influenced means within said reservoir arranged to travel through said liquid toward and away from the axis of pivoting of said reservoir, over-center resilient means operatively connected between said reservoir and said support which opposes downward pivotal movement of the reservoir in one over-center position and accelerates said movement in the other over-center position, means for holding said reservoir in an uncocked position inclined upwardly to said axis of pivoting to permit said gravity influenced means to travel toward said axis of pivoting, and releasable latch means for permitting said reservoir to pivot downwardly when cocked to a position inclined downwardly from said pivotal axis whereby said gravity influence means travels to a point away from said pivotal axis where its effective leverage together with the weight of said body of liquid and said reservoir overbalance said resilient means and cause said resilient means to pass over to the other side of center position and thereby snap said reservoir downwardly to a position below said cocked position, and means for automatically returning said reservoir to the said uncocked position after it has been snapped downwardly by said over-center resilient means.

9. A timing device comprising a support, a reservoir containing liquid and pivotally supported on said support, mechanism control means arranged to be actuated by said reservoir as it pivots to its most downwardly position, a pivotal stop member of restricted movement, over-center resilient means acting between said support and said stop member and tending to hold said reservoir in a position downwardly inclined to the pivotal axis thereof, and gravity influenced means within said reservoir adapted to travel away from its axis of pivoting and thereby overcome the tendency for said resilient means to hold said reservoir in said downwardly inclined position whereby said over-center means passes to the other side of center position and allows said reservoir to freely pivot downwardly under the influence of said gravity influenced means thereby gathering momentum and abruptly actuating said control mechanism as it reaches its most downwardly position.

THOMAS H. SHEEHAN.
